TELEPHONE & TELEGRAPH COMPANY, OF JERSEY CITY, NEW JERSEY, A CORPORA-
TION OF DELAWARE

ELECTRON DISCHARGE DEVICE AND PROCESS OF MAKING THE SAME

No Drawing.

Application filed May 10, 1924. Serial No. 712,456.

This invention relates to electron discharge devices and the process of making the same, and more particularly to the means and method for reducing the residual gases and activating the filament.

The objects of the invention are to provide an improved means and method of reducing the residual gases and activating the filament in an electron discharge device; to use a flashing material which may be readily handled without detriment to the material or injury to the operator; to provide a material which can be flashed and which will have maximum effect; to employ the element iodine as a flashing material; to also employ potassium as a flashing material; to utilize a salt as the flashing material; to obtain a decomposition of the salt in order to effect a flash of the tube; to employ a means for decomposing the salt which also has a beneficial action upon the filament; to secure simplicity of construction and operation, and to obtain other advantages and results as may be brought out in the following description.

In carrying out my invention, I preferably employ an electron emissive filament in combination with the usual plate and grid within an evacuated vessel. It has been common practice to employ some substance, usually magnesium, for flashing the device while the same is being pumped so as to reduce the residual gases and obtain as high a degree of evacuation as possible.

Preferably the material which is employed for flashing the electron discharge device in accordance with the present invention is a salt which may be decomposed into one or more active materials which in the free state will be active as a flash at a much lower temperature than magnesium.

I have known of the desirability of potassium and iodine as flashing material, but heretofore have not been able to commercially use the same for the reason that they are very difficult to handle in a free state, being both injurious to the operator and difficult to control. I now find that by utilizing a salt of one or both of these materials that I can handle the salt very readily and without injury. The salt may be decomposed within the

electron discharge device at the time and place desired and at such time the free element will effect a reduction of the residual gases. I have further found that it is not only possible but advantageous to employ a salt containing both the element potassium and the element iodine such as potassium iodide. When these two elements are liberated in the free state, they are exceedingly active and effective.

In order to decompose the salt of potassium and iodine, I find that an alloy of magnesium and calcium associated therewith, and heated, will have a disrupting effect upon the salt and cause the same to separate into its constituent elements. The use of this alloy of magnesium and calcium is doubly advantageous because it not only decomposes the salt, but also operates to combine with oxygen and activate the filament by reducing the oxide coating thereon so the filament will have an exposed surface of free metal. Here it is to be understood that filaments such as the frequently used mixture or coating of thorium freely oxidize when exposed to the air and will almost invariably be applied to the electron discharge device as thorium oxide. It has always been necessary to change at least a portion of the oxide before the filament can be made to emit electrons. Use of the alloy above mentioned therefore accomplishes this purpose as well as decomposing the salt above mentioned.

In use, I prefer to mix the alloy and salt in powder form, although it is deemed within the scope of the invention to associate the alloy and salt in any manner which will cause the one to react upon the other at the desired time. The mixture in powder form can be secured to the plate of the electron discharge device in any suitable manner as by use of paste or mechanical agencies. The specific manner in which the mixture is secured or held not being part of the present invention, no further mention need be made thereto at this time.

In carrying out the process which I have invented the salt and alloy are preferably mixed and applied to the plate during the course of manufacture, and while the tube is

on the pump being evacuated, the temperature of the alloy is raised by any suitable means, such as electron bombardment, and the temperature being sufficient, the alloy 5 flashes or vaporizes, acting upon the salt to break it up into its constituent elements which likewise flashes or vaporizes, both operating to reduce the residual gases in the tubes so as to improve the degree of evacuation therein.

10 Obviously detail changes and modifications may be made in the manufacture of my improved electron discharge device, and process by which the same is made, and I do not wish to be understood as limiting myself to the exact combination of elements or other like matter or to the exact steps and process mentioned, except as set forth in the following claims when construed in the light of the prior art.

15 Having thus described my invention, I claim:

1. The method of manufacturing an evacuated electron discharge device having an electron emissive cathode, which comprises introducing a chemical compound of potassium and iodine in the presence of an alloy of magnesium and an alkaline-earth metal into the device and heating said chemical compound to liberate the elements thereof so 20 that they may react with the gases within the device.

2. In the method of manufacturing electron discharge devices comprising a vessel and a plurality of electrodes therein including the steps of introducing a chemical compound of potassium and iodine into the vessel and an alloy containing magnesium and an alkaline-earth metal and heating said alloy to break it down and cause it to act upon 35 said chemical compound to break it up into its constituents.

3. In the method of manufacturing electron discharge devices comprising a vessel and a plurality of electrodes therein including the steps of introducing a chemical compound of potassium and iodine into the vessel and an alloy of magnesium and calcium and heating said alloy to disrupt it.

4. In the method of manufacturing electron discharge devices comprising a vessel and a plurality of electrodes therein including the steps of introducing a chemical compound of potassium and iodine into the vessel, and an alloy of calcium and magnesium 55 and heating said alloy to disrupt it and effect decomposition of said chemical compound.

5. The herein described process which comprises heating an alloy containing magnesium and an alkaline-earth metal in the presence of a salt containing iodine in an evacuated vessel and heating the alloy while in said vessel.

6. The method of manufacture of electron discharge devices comprising the steps of introducing into the envelope of the device a

halide containing iodine and an alloy containing magnesium and an alkaline-earth metal, and flashing magnesium alloy to produce a free halogen for cleaning up residual gases within the device.

7. The method according to claim 6 in which the magnesium alloy is flashed by heating.

8. In the manufacture of electron discharge devices the method of liberating a free halogen within the envelope of the device which comprises heating an alloy of magnesium and calcium in the presence of a halide within said envelope.

9. In the manufacture of electron discharge devices the method of reducing residual gases which comprises introducing a halogen salt and an alloy containing magnesium and an alkaline-earth metal into the envelope of the device, and flashing the alloy 85 to liberate a free halide from the salt.

10. In the manufacture of electron discharge devices the method which comprises introducing into the interior of the envelope of the device a quantity of salt containing iodine and an alloy containing magnesium and an alkaline-earth metal and flashing the alloy in the presence of said salt to liberate free iodine.

11. The method according to claim 10 in which the alloy is flashed by electron bombardment.

12. The method according to claim 10 in which the alloy contains calcium.

13. The method according to claim 10 in which the salt contains potassium and iodine.

14. The herein described process of producing free iodine which comprises introducing an alloy containing magnesium and calcium and a salt containing iodine into the 105 evacuated vessel, and flashing the alloy to disrupt the salt and produce free iodine.

15. The process according to claim 14 in which the alloy is flashed by heat.

16. An electron discharge device comprising an evacuated envelope, a quantity of alloy containing magnesium and an alkaline-earth metal, and a salt of iodine applied to a portion of the interior of the envelope.
